UNITED STATES PATENT OFFICE.

ERNEST F. CHESTER AND CHARLES P. CHESTER, OF NEW YORK, N. Y.

AMUSEMENT APPARATUS.

Application filed December 7, 1922. Serial No. 605,408.

To all whom it may concern:

Be it known that we, ERNEST F. CHESTER and CHARLES P. CHESTER, both citizens of the United States, and residing at the city of 5 New York, borough of Manhattan, in the county of New York and State of New York, have invented a new and Improved Amusement Apparatus, of which the following is a full, clear, and exact description.

10 This invention relates to an amusement apparatus and its object is to provide a new and improved game, preferably a multi-contestant game, for use in pleasure resorts, exhibition grounds, fairs, parks and other 15 places, and arranged to enable a number of contestants or players to participate in a speed contest of marksmanship.

Another object is to permit a number of contestants to discharge missiles at various 20 rates of speed at a plurality of distant target means to contest for a prize awarded to the winner.

Another object is to render the chances of success equal to all contestants; and preferably in that connection to provide an 25 amusement apparatus whereby the same number of missiles may be thrown by each contestant during a predetermined time interval which is the same for all contestants.

30 Another object is to provide an amusement apparatus such that all missiles thrown by all contestants will eventually be directed toward a master reservoir adapted in turn automatically to replenish the separate reservoirs individual to the missile-projecting means allotted to each contestant.

Another object is to associate with each 35 missile-projecting means fixed guiding surfaces in each, with all such guiding surfaces relatively immovable, so that each projecting means is adapted to discharge its missiles toward the particular target means allotted to that projecting means.

Another object is preferably to construct 40 each such target means as a receptor for a plurality of missiles, in combination with means for releasing such missiles and signalling the fact of such release, when the missiles received by any target means total a predetermined plurality.

Another object is to construct an amusement apparatus which is highly attractive in its various features and provides an interesting show for the participants as well as 45 for the onlookers.

In the latter regard, a more specific object

of the invention, so far as an embodiment of the same as at present preferred is concerned, is to provide an amusement apparatus comprising a plurality of contesting mechanical mannikins, each located, presenting an appearance, and having a limb manually actuatable as an always exposed missile-ejecting instrumentality, characteristic of a well-known athletic contest, such as the game of football, and a plurality of target means facing such mannikins at some distance therefrom and designed in simulation of goal posts or goal baskets for receiving one or more missiles suggesting the projectile 60 object of play of such contest, as a football.

With these and other objects in view, the invention consists of certain novel features of construction and combinations of parts as hereinafter shown and described and then specifically pointed out in the claims.

The invention will be more clearly understood from the following description, when taken in connection with the accompanying drawings, showing, as one example of a possible way the invention may be carried out, a game in simulation of a football contest.

In these drawings:

Fig. 1 is a transverse view taken on the line 1—1 of Fig. 3, and showing the target 65 means in front elevation;

Fig. 2 is a top plan view;

Fig. 3 is a longitudinal section, taken through one of the target means and its appropriate missile-projecting means;

Fig. 4 is an enlarged detail view, showing 70 certain of the parts of Fig. 3 at a target means;

Fig. 5 is an enlarged detail view showing certain of the parts of Fig. 3 at a projection 75 means;

Fig. 6 is a fragmentary view, showing in top plan certain of the missile feeding and guiding means shown in Fig. 5 in section and in side elevation;

Fig. 7 is a view generally similar to Fig. 5, but showing a modification; and

Fig. 8 is a detail view, partially in elevation and partially in section, showing a structural variation of the preferred missile-ejecting member and its mount.

Similar reference characters refer to similar parts through the several views of the drawings.

A line of targets 8 are served by a similar line of projecting means 9. It will be noted, most clearly from Fig. 1, that each target

- means 8 resembles in appearance one of the goals of a football field, while, as seen best in Fig. 3, each projection means is a mannikin apparently dressed in football uniform.
- 5 Each such mannikin is allotted to one of the targets 8; and referring now momentarily to Fig. 5, the ejector proper for each missile 10, supplied from a suitable store thereof, for the mannikin 9, is a foot 11 at 10 the end of a swingable leg member 12 doubly pivoted at 13 and 14.
- 10 A missile 10 simulates in appearance and trajectory, when projected by a kicking motion of the mannikin's foot 11, toward the 15 allotted target 8, the projectile object of play, or football, of a football game.
- 15 In order to provide means to cause such trajectory of a missile 10 to result from a forward kicking motion of the foot 11 of a 20 mannikin, when such missile is located as indicated at 10' in Fig. 5, the following parts are provided in association with each mannikin and within a compartment 15 below a floor 16 on which the mannikin is fixed 25 upright by means of its rigid leg 17. Slidably mounted in underlying guide blocks 18, is a vertical plate 19 having an S-shaped upwardly extending fixed arm 20 pivoted to foot 11 at 21. This plate, normally held in 30 the position shown in Fig. 5 by means of a spring 22, has a horizontal line of ratchet teeth on an upper edge of the plate as indicated at 23. An upright handle 24, pivotally mounted at its lower end at 25, carries a rockable claw-rod 26 pivoted on the handle at 27. This rod 26 has at its forward end a hook 28 and at its rear end a roller 29. This roller is provided for riding against a ramp device 30, thereby to rock 35 the rod 26 upward from a bottom stop 31 on the handle, when the handle is moved slightly further to the right in Fig. 5 than there illustrated. Once the parts 32 and 33 are released, as will be understood in a moment, it will be seen that a throw of the handle 24 to the left throws the hook 28 in that direction to the right over the backs of teeth 23, and that the subsequent retraction 40 of the handle to the right slides the plate 19 to retract the foot 11 of the mannikin as indicated by the arrow 34. It will also be noted that toward the latter part of such retraction stroke of the handle, the roller 45 29 engages the ramp 30 and is disposed thereby to release the hook 28; whereupon the spring 22 snaps the plate 19 back to the illustrated position and swings foot 11 forward toward the missile at the location 10'. When the missile is thus impacted or kicked 50 to be shot toward the left of Fig. 5, the missile is caused to rise upward, due to the presence of a hummock 35, and the direction of flight given the missile is toward the target 8 allotted to this mannikin, due 55 to a pair of guide-rails 36.

Such hummock and guide-rails, it will be seen, constitute fixed surfaces for guiding the exposed missile to describe a high fly to clear a fence 37 (Figs. 2 and 3) and advance toward the proper target. It will also be noted that the projection means proper for such exposed missile is a visibly operating, or exposed, ejecting instrumentality for the missile, the foot 11.

60 A handle 24 and appurtenant parts as just described, are of course associated with the mannikin of each projection means, and consequently such handle 24 is seen in Fig. 2 in its slot alongside each mannikin. It will be understood that all the individual contestants play the game simultaneously, each operating one of the handles 24; and each endeavoring to operate the handle at the maximum rate of speed permissible to kick out the greatest number of missiles in a given interval of time, and yet without pumping the handle 24 back and forth so rapidly as to defeat the guiding functions of the hummock 35, the guide-rails 36, and, particularly the predetermined straight-line 85 thrusts of the kicking foot of the mannikin.

80 In order to provide means to prevent any contestant from starting to pump his handle 24 before another contestant, the following parts are provided, to wit, the parts 32 and 33 above passingly referred to. The part 32 represents a hooked collar, one of which is fixed on each handle 24 at about the point indicated in Fig. 5. These collars 32 are arranged in horizontal alignment 90 transverse to the apparatus. The part 33 is a transverse bar extending across the entire width of the apparatus and having at opposite ends an offset arm as indicated at 37 in Fig. 5: these two arms being pivoted on a single horizontal axis as indicated at 38 in Fig. 5 in the case of the arm 37 shown there. Fixed to the latter arm is a handle 39 adapted to be thrown to the left of Fig. 5, by an attendant, simultaneously to release all the handles 24. If desired, the parts just described may be employed to lock all the handles 24, when, upon the occurrence of a suitable signal, the contestants cease actuating the handles 24.

100 Still referring primarily to Fig. 5, the following parts are provided in order to feed a new missile to each mannikin just before the foot 11 thereof is given a forward kicking motion by a forward pumping stroke of the associated handle 24. Below each mannikin, in compartment 15, is what may be termed a T-shaped well or individual reservoir for a store of missiles 10. It will be noted that the head of the T is a vertical tube 110 40 having a movable bottom constituted by a plunger 41. The stem of the T is an inclined, gravity-feed tube 42 for holding a plurality of the missiles in tandem relation. Thus, with the plunger 41 as shown, the for- 115 120 125 130

ward one of the missiles in the inclined line of the tube 42, lies in the tube 40 and centers itself in the upper downwardly dished surface of the plunger. This plunger has a pending centrally reduced stem 43 carrying a roller 44 at its lower end. When handle 24 is pumped forward or to the left of Fig. 5 to engage hook 28 with the breast of a ratchet tooth 23 toward the left-hand of the line of such teeth, thereby to actuate the foot 11 of the mannikin to kick out the missile then at the location 10', and said handle is thereupon pulled back to retract said foot 11, the ramped edge 45 of plate 19 coacts with roller 44 to give plunger 41 a full upstroke and thus elevate the missile overlying the top of the plunger to the location 10'. At the next forward pumping action of handle 24 foot 11 kicks out this second missile at the location 10'; plunger 41 meanwhile descending to receive the leader of the missiles 10 in inclined tube 42.

In order to provide means for holding a missile elevated as just described, at the location 10', despite the descent of the plunger 41 during the forward swing of the mannikin's foot toward such elevated missile, a pair of pivoted latches are provided as indicated at 46; these latches being gravity-held to the positions shown in Figs. 5 and 6.

In order to keep the individual reservoirs of each projection means supplied continuously with a plurality of missiles 10, it will be seen, by comparing Figs. 2 and 3, that each inclined tube 42 is a branch conduit leading from a main transverse conduit 47, in turn fed by a pair of inclined conduits 48 at opposite sides of the apparatus. These side conduits 48, as shown best from a comparison of Figs. 1 and 3, are fed from a missile-receiving compartment 49 extending across the width of the apparatus and below the line of targets 8 behind a far fence 50. It will be noted that the floor of compartment 49 is highest at its center and inclined downwardly in opposite directions toward the side conduits 48. The collection of parts just described may be called the master reservoir for the individual reservoirs of the various projecting means.

Of course, all the thrown missiles which miss the targets 8 are received beyond the fence 50 and enter the master reservoir.

Referring now to Figs. 3 and 4, it will be seen that each target means is a receptor for the missiles, and has a central opening 51 corresponding to the space between goal posts or a goal basket. Associated with each opening 51 are means for detaining inside each target all the missiles received by the same, until a predetermined plurality of missiles is so received, and for automatically thereupon releasing all the received missiles and simultaneously giving a signal of the fact that such missiles are released and

consequently that the contestant allotted to that target has won the contest, by being the first to project into his allotted target the predetermined plurality of missiles during the course of the contest just concluded. 70 The means for attaining these ends include the following parts. Opening 51 continues as a vertical tubular pocket 52, the lower end of which is normally closed by means of an arm 53 of a lever pivoted at 54 and normally over-weighted by a rearwardly extending arm 55 so as to close the bottom of pocket 52. The design of these parts is such that the weight of the predetermined plurality of missiles, say three as indicated in broken 80 lines in Fig. 4, is just enough to rock the lever to the broken line position shown. The moment the lever is thus rocked, the missiles in the compartment are discharged into the main reservoir, and simultaneously a normally open circuit 56, served by a battery 57, is closed at a contact 58 and a visible electric bulb 59 is lighted.

The lighting of such bulb 59 of course indicates the winner of the contest. 90

At the conclusion of a particular contest, a suitable master-switch (not shown) for closing a circuit (not shown) to actuate individual electro-magnets (not shown) for the arms 24 of all the levers of the targets 95 8, may be manually closed to add such missiles as have not been delivered to the pockets of such targets during the contest just concluded, to the main reservoir. Or, all such levers may be manually rocked in any 100 suitable way by the attendant to collect the missiles from all the compartments. At that time, also, the attendant may collect up all the missiles on the inclined floor marked 60 in Fig. 3, which have collected there as the 105 result of rebounding from the faces of the targets 8 surrounding their central openings; and these missiles may be thrown into compartment 49 and so added to the missiles of the main reservoir. It will be understood 110 that preferably a large surplus of missiles, in practice about three hundred, will always be supplied so that there will be no lack of missiles in the tube 42 feeding each projection means. 115

In Fig. 7 is indicated a possible modification of the parts associated with each mannikin 9 as in Fig. 5. In Fig. 7 an upright handle 24^a is used, pivoted at 25^a in the bottom of compartment 15. The parts 18, 22, 43 and 44 are similar in function to the same parts in Fig. 5. The plate 19^a is the same as plate 19 of Fig. 5, except that the ratchet teeth 23 and the arm 20 are omitted. It is also desirable in the case of the plate 19^a to provide an auxiliary guide block 61. Handle 24^a is directly connected to the kicking foot of the mannikin, as by a pivot stud 62, and is permanently operably connected to plate 19^a as by a fixed post 63 upstanding 120 125 130

from the latter and a link 64 joining the top of the post and the handle. This is a simplified construction, and one whereby the contestant may rely upon his own muscular power to impart the forward kicking movement to foot 11.

Two other important features of the invention will now be described, one or both of which may desirably be incorporated in 10 the new combination.

Referring to the first of such additional features, examine Fig. 5. It has been hereinabove pointed out, in the paragraph beginning in the middle of page 2 and with 15 reference to handle 24, that each contestant will naturally endeavor to operate his handle 24 at the maximum rate of speed permissible to kick out the greatest number of missiles in a given interval of time, and yet without 20 pumping the handle back and forth so rapidly as to defeat or impair the guiding functions of hummock 35 and guide rails 36 of the missile-aiming means. In this connection, further, we have discovered that if 25 the rockable claw-rod or lever 26 as viewed in Fig. 5 be properly overweighted to the right of its pivot 27, as by a proper extra weight 26' if necessary, any pumping of handle 24 toward its mannikin at too rapid 30 a speed, will cause hook 28 to engage the back of the first contacted ratchet teeth 23 at such a pressure or velocity as to kick the hook high enough above said teeth to preclude 35 whole or partial retraction of plate 19 with lever 26 on a retraction of handle 24.

Referring, finally, to the second of such additional features, compare Fig. 8 with the corresponding parts of Figs. 5 and 7. It will be noted that the kicking foot of Fig. 8, 40 marked 11^a, is not rigidly carried at the ankle of the kicking limb 12 of the mannikin, but instead is mounted in such a way as to be rather freely wabbable on the lower 45 end of said limb, if the limb is too rapidly moved, by a too rapid movement of the associated handle 24, toward a missile. Thus, this feature of construction has a purpose somewhat akin to the purpose of the feature described in the paragraph immediately preceding. To these ends, the upper portion 50 of the foot 11^a is recessed as illustrated to provide a loose socket for the lower ball-end of the limb 12, and foot and limb are further pivotally connected by a cross-pin 55 11^b loose in both foot and limb, also as illustrated. It will be understood that if the handle 24 is worked at a permissible speed, that is, not too rapidly to set up a side sway of the kicking limb or relative movements 60 between the jointed parts of said limb and the foot due to vibration, gravity will hold the foot in proper kicking position on the limb to allow the hummock 35 and guide rails 36 to perform their appointed functions; but not otherwise.

We will state in conclusion that while the illustrated example constitutes a practical embodiment of our invention, the same is merely an example of one of the multitude of ways in which the same may be carried out, and we do not limit ourselves strictly to the exact details herein illustrated, since, manifestly, the same can be considerably varied without departure from the spirit of the invention as defined in the 70 appended claims.

We claim:

1. In a multi-contestant game, the combination of target means, a plurality of separately operable missile-projecting means 80 each including a manual actuator, normally ineffective locking means for each projecting means, and means manually operable at will to render all said locking means simultaneously effective.

2. In a multi-contestant game, the combination of target means, a plurality of separately operable missile-projecting means each including a manual actuator, each such actuator being normally operable independent of the operation of any other actuator, a locking device for each actuator, and means common to the locking devices for rendering all said devices effective or ineffective simultaneously.

3. In a game, the combination of a target means, means for projecting a missile toward said target, positioning means for the missile at the instant of projection, and an actuating means operatively connected to 100 the projecting and positioning means, said positioning means including a fixed structure formed with a recess and including a movable structure carrying a missile supporting wall constituting one of the walls 105 of said recess.

4. In a game, the combination of a target means, means for projecting a missile toward said target, positioning means for the missile at the instant of projection, and 110 an actuating means operatively connected to the projecting and positioning means, said positioning means including fixed structures adapted to engage the sides of the missile at the instant of projection to affect the direction of flight thereof.

5. In a game, the combination of a target means, means for projecting a missile toward said target, positioning means for the missile at the instant of projection, and 120 an actuating means operatively connected to the projecting and positioning means, said positioning means including a structure for engaging the under side of the missile to affect the direction of flight thereof.

6. In a game, the combination of a target means, a projecting means operable for discharging a plurality of missiles toward said target means, a manual actuator for said projecting means, a reciprocating means also 130

operated by said actuator for feeding a missile to the field of operation of the projecting means at each operation of the actuator and near the end of a stroke of said reciprocating means in one direction, and means 5 for feeding a missile to said reciprocating means after the end of a stroke of the latter in the opposite direction.

7. In a game, the combination of a target 10 means operable for discharging a plurality of missiles toward said target means, a manual actuator for said projecting means, means for feeding missiles to the projecting means, said feeding means including a structure having a substantially vertical bore 15 open at the top and at one side, a plunger reciprocating in said bore at each operation of the actuator, the plunger at the end of its down stroke clearing the opening in the side of the bore, and means for feeding a 20 missile through the side opening of the bore and atop the plunger when the latter is positioned as last described.

8. In a game, the combination of a missile 25 projecting means including a swingable missile projector member, means for feeding missiles into the field of swing of said projector member and including a vertically reciprocable member, a manually movable 30 actuator, and operative connections between said actuator and said two members and for causing movements of the two members to have movements toward each other on a movement of the actuator, the two members 35 being mounted and guided for movements such that the path of movement of the reciprocable member is substantially normal to the arc of movement of the swingable member.

9. In a game the combination of a missile, 40 projecting means including a movable missile supporting means, a striker member movable to strike a missile when supported by said supporting means when said supporting means is in a predetermined position, said supporting means comprising a 45 lifter member reciprocable at a considerable angle to the path of movement of the striker member and for supporting and advancing 50 a missile to said predetermined position, an actuator, means including operative connections between the actuator and the two members for simultaneously moving said members when the actuator is moved, and means 55 for varying the relations of the movements of said members in accordance with the amplitude of movement of the actuator.

10. In a multi-contestant game, the combination of a plurality of spaced target 60 means, a collecting structure for missiles projected toward the target means, a plurality of spaced means for projecting missiles toward said target means, a reservoir for a plurality of missiles associated with 65 each projecting means, means for automati-

cally feeding a missile to each projecting means from its associated reservoir on actuation of said projecting means, a master reservoir, and means for replenishing all the target reservoirs from said master reservoir. 70

11. In a multi-contestant game, the combination of a plurality of spaced target means, a plurality of spaced means for projecting missiles toward said target means, 75 normally inoperative signalling means associated with each of the target means, and controlling means for each signalling means and disposed for impingement by missiles and for automatically rendering operative 80 said signalling means when said controlling means is impinged by a certain predetermined plurality of missiles but for maintaining said signalling means inoperative until said controlling means has been impinged by said plurality of missiles following the setting of signalling means to inoperative condition, there being provided manual means for setting the signalling means to inoperative condition after each 85 operation of said signalling means.

12. The game defined in claim 11, wherein in the controlling means has associated therewith a normally operative detent for received missiles, said detent including a 95 gravity-responsive releasing means for said detent actuated upon the reception of said plurality of missiles.

13. In a multi-contestant game, the combination of a plurality of spaced target 100 means each constituting a receptor for a plurality of missiles, a plurality of spaced means for projecting missiles toward said target means, a missile support movably 105 associated with each target means and including a gravity-responsive element for discharging all the supported missiles when and only when a predetermined plurality thereof is supported, and signalling means 110 associated with each target means for indicating when such supported missiles are so discharged.

14. In a multi-contestant game, the combination of a plurality of spaced target 115 means each constituting a receptor for a missile, and a plurality of spaced means for projecting missiles toward said target means, a reservoir for a plurality of missiles associated with each projecting means, means 120 for automatically feeding a missile to each projecting means from its associated reservoir on each actuation of said projecting means, a master reservoir, and means for replenishing all the target reservoirs from 125 said master reservoir.

15. The game defined in claim 14, wherein means are provided for supplying said master reservoir with missiles received by all the target means. 130

16. In a game, the combination of a target

means, a missile-projecting means including a plurality of relatively movable parts, a manual actuator for operating one of said parts relative to the other, and a support for a missile at the instant of projection, said support being immovable relative to the target means and the projecting means and including missile-guiding surfaces, said actuator being operable at different speeds 10 at will, said parts being loosely connected and held by gravity to certain relative movements when said actuator is operated at a certain speed, whereby when said actuator is operated at a greater speed said parts 15 will have different relative movements thereby to impair the efficacy of such surfaces.

17. The game defined in claim 14, wherein means are provided for supplying said master reservoir with missiles received by all 20 the target means, each target means having associated therewith a normally operative detent for received missiles, said detent including a gravity-responsive releasing means therefor actuated upon the reception of a 25 predetermined plurality of missiles by said detent.

18. The game defined in claim 14, wherein means are provided for supplying said master reservoir with missiles received by all 30 the target means each target means having associated therewith a normally operative detent actuated upon the reception of a predetermined plurality of missiles, there being provided individual locking elements 35 for each projecting means, a locking device adapted to coact with all said locking elements to lock all the projecting means simultaneously, and means for disengaging said locking device from all said locking elements simultaneously. 40

19. In a game to be played by casting missiles at a target, a target structure defining a goal area and including an opening within said area, a movably mounted 45 missile-receiving support in rear of said opening, a signal means, and means to actuate said signal means upon a predetermined movement of said support, said support having a missile-receiving and detent 50 portion so shaped and disposed relative to the movable mounting of said support that the support remains immovable and retains less than a predetermined plurality of missiles received thereby but is given said predetermined movement upon said portion receiving and retaining the complete plurality 55 of missiles predetermined.

20. A game of skill to be played by projecting a plurality of missiles in rapid succession at a distant target, said game including means for projecting missiles at said target, means for returning previously projected missiles to the vicinity of the projecting means, means for actuating the projecting means, means for transferring one of the 60 65

missiles last-mentioned to the field of operation of the projecting means, a variable-speed manual controller for the projecting means, and means operable by said controller to actuate the feeding means in timed relation to the operation of the projecting means but only when said controller is moved at a speed above a predetermined maximum. 70

21. In a game of skill including a projectile and to be played in simulation of the kicking features of an actual football game, the combination of a target representant of a goal point, a mannikin including a relatively movable kicking limb, means for actuating said limb to cause the same to retract and to move forward to kick a missile presented at a point between mannikin and target, said means including a spring urging said limb toward a kicking movement, 80 and means for feeding missiles to said point between kicks, said means including a vertically reciprocating plunger, a chute shaped to hold a plurality of missiles in column, said chute having a movable bottom wall 90 constituted by the top of the plunger, and means for automatically retracting the limb against said spring, for elevating the plunger and for releasing the limb to the action of the spring during the course of 95 such reciprocation of the plunger.

22. A game of skill to be played by projecting a plurality of missiles at a target, said game including means for projecting missiles at said target, a reservoir for missiles in the vicinity of the projecting means, means for actuating the projecting means, means for transferring one of the missiles last-mentioned to the field of operation of the projecting means, a manual controller 100 for the projecting means and for the transferring means, and means operable automatically on actuating the controller at a certain speed, thereby to render, for that actuation, said transferring means inoperative. 105

23. A game of skill to be played by projecting a plurality of missiles at a target, said game including means for projecting missiles at said target, a reservoir for missiles in the vicinity of the projecting means, means for actuating the projecting means, means for transferring one of the missiles last-mentioned to the field of operation of the projecting means, a manual controller for the projecting means and for the transferring means, said controller being selectively variously manually operable, and means for predeterminedly and according to the mode of operation of said controller rendering the transferring means and the projecting means both inoperative on certain actuations of said controller. 115 120 125
